US00D867293S

(12) **United States Design Patent** (10) **Patent No.:** **US D867,293 S**
Fukuyama (45) **Date of Patent:** **** Nov. 19, 2019**

(54) **TERMINAL METAL FITTING FOR ELECTRICAL CONNECTOR**

(71) Applicant: **SUMITOMO WIRING SYSTEMS, LTD.**, Mie-ken (JP)

(72) Inventor: **Kyoko Fukuyama**, Yokkaichi (JP)

(73) Assignee: **SUMITOMO WIRING SYSTEMS, LTD.**, Yokkaichi-Shi, Mie-Ken (JP)

(**) Term: **15 Years**

(21) Appl. No.: **29/666,834**

(22) Filed: **Oct. 16, 2018**

(30) **Foreign Application Priority Data**

Apr. 20, 2018 (JP) 2018-008776

(51) **LOC (12) Cl.** **13-03**

(52) **U.S. Cl.**

USPC **D13/133**

(57) **CLAIM**

The ornamental design for a terminal metal fitting for electrical connector, as shown and described.

DESCRIPTION

FIG. 1 is a front, top and right side perspective view of a terminal metal fitting for electrical connector showing my new design;

FIG. 2 is a rear, bottom, and left side perspective view thereof;

FIG. 3 is a front view thereof, the rear view being a mirror image of FIG. 3;

FIG. 4 is a top plan view thereof;

FIG. 5 is a bottom plan view thereof;

FIG. 6 is a right side view thereof; and,

FIG. 7 is a left side view thereof.

1 Claim, 5 Drawing Sheets
